UNITED STATES PATENT OFFICE.

WALTER SHAW, OF DEDHAM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENER-SETTING MACHINE.

1,296,014.

Specification of Letters Patent.

Patented Mar. 4, 1919.

Application filed July 8, 1916. Serial No. 108,174.

To all whom it may concern:

Be it known that I, WALTER SHAW, a citizen of the United States, residing at Dedham, in the county of Norfolk and State of Massachusetts, have invented certain Improvements in Fastener-Setting Machines, of which the following description, in connection with the accompanying drawings, is a specification, like reference characters on the drawings indicating like parts in the several figures.

This invention relates to machines for setting eyelets, lacing hooks or similar fastening devices in sheet material and particularly to machines of the duplex type, although certain features of the invention may be embodied with advantage in single machines.

Heretofore duplex machines have been so organized as to insert hooks or eyelets from the outside of a folded shoe upper, with the barrels of the fasteners pointing toward each other. In one of its aspects the present invention consists of a duplex machine organized to insert fasteners from within a folded upper, with the barrels of the fasteners extending outwardly in opposite directions. A machine so organized is adapted to receive an upper presented to it inside out so that the lining and the clenched end of the fastener barrel may be readily inspected by the operator. There is little question that the flanged or previously formed head of the fastener will be properly set upon the work but the character and shape of the clenched end of the fastener barrel must be carefully observed to make certain that the setting operation is carried out properly.

An important advantage of a duplex machine organized in this manner is that it may be employed to insert invisible eyelets simultaneously in both sides of an upper presented to the machine right side out. This has never before been successfully accomplished, and, in another of its aspects therefore, the invention comprises a duplex machine organized for the insertion of oppositely disposed pairs of invisible eyelets in a folded shoe upper.

A novel feature of the invention consists in means for feeding fasteners between the spaced sides of a folded upper so that they may be inserted from the inside of the upper, *i. e.*, from a position between its folded sides, with their barrels extending outwardly. As above intimated, duplex machines as heretofore constructed have been provided with raceways for feeding the fasteners into positions outside a folded upper whence they are subsequently inserted by movement toward each other. In the machine herein shown eyelets are delivered in pairs arranged back to back between the sides of the upper and are clenched while maintained in such relation.

Another feature of the invention consists in means for engaging an eyelet or fastener in the raceway through a hole previously punched in the upper, and withdrawing the fastener from the raceway. Heretofore it has been customary to provide a pin or spindle for this function, but, in accordance with one feature of the present invention, the setting die itself is utilized and the construction of the machine thus simplified while at the same time its accuracy is increased. This feature is obviously not limited in its application to a machine of the duplex type.

Still another feature of the invention consists in a raceway constructed and arranged to support the eyelet or fastener during the upsetting operation. This feature is of importance in a machine of the duplex type in facilitating the presentation of fasteners between the spaced sides of the folded upper, requiring the minimum amount of separation of the sides of the upper to admit the fasteners.

Another feature of the invention consists in novel means for removably mounting the plunger lifting levers of a machine of the type disclosed in United States Letters Patent No. 934,066, granted September 14, 1915, on an application of G. Goddu.

These and other features of the invention will be best understood and appreciated from the following description of a preferred embodiment thereof selected for pur-

poses of illustration and shown in the accompanying drawing, in which,—

Figure 1 is a plan view of the operative instrumentalities of a duplex machine embodying the invention;

Fig. 2 is a view in perspective of parts of the machine shown in Fig. 1;

Fig. 3 is a sectional view of the mounting for the plunger lifting levers;

Figs. 4 to 7 are views in elevation, partly in section, illustrating successive steps in the operation of the machine;

Figs. 8 and 9 are plan views corresponding to Figs. 6 and 7 respectively.

The invention is herein illustrated as embodied in a duplex eyeleting machine of the character shown in the patent to Goddu identified above, and parts of the machine not specifically referred to below may be similar to the corresponding parts of the Goddu machine. As in that patent, the machine frame 2 is provided with journals for a shaft 4 carrying at one end clutch mechanism, not shown, and a series of operating cams disposed intermediate of its length. A bell crank cam lever 8 is pivotally mounted upon a stationary spindle 6 set in the machine frame and carried at its outer end a head 10 in which the punching and setting instrumentalities of the machine are mounted. At its rear end the lever 8 carries a cam roller which runs in a cam 12 on the shaft 4, the cam 12 being shaped to swing the lever 8 and shift the head 10 forwardly and rearwardly as will be explained hereinafter.

A second cam lever 16 is pivotally mounted upon the frame and connected to the head 10 through a pair of links 18 and 20 which impart a transverse or lateral movement to the head 10 when the lever 16 is oscillated by a cam 14 on the shaft 4. This transverse movement of the head 10 is utilized in feeding the work and its extent is controlled by a lever 22 by which the action of the links 18 and 20 may be varied as explained at length in said patent.

The head 10 has upper and lower branches in each of which is formed a pair of parallel bearings for the punches and upsetting dies. Plungers 24 carrying the upsetting dies are mounted in the outer bearings and plungers 26 for the punches are mounted in the inner bearings of the head 10. These plungers are forced toward each other at the proper point in the cycle of the machine by oppositely disposed hammer operating levers 30, only one of which is visible in the accompanying drawings. The set plungers 24 are each connected with an arm 32 and the punch plungers are each connected with an arm 34. Tension springs extend between each pair of arms and serve to retract the respective plungers after they have been operated by the hammer levers.

The mounting of the plunger retracting arms is clearly shown in Figs. 2 and 3. An outwardly extending tube 36 is rigidly secured in a rib formed in each branch of the head 10 and the set, lifting arm 32 is journaled upon the tube 36 at the right side of the rib of the head 10 as shown in Fig. 3. A threaded pin 38 passes loosely through the tube 36 and has secured to its inner end one of the lifting arms 34 for the punch plungers. At its outer end the tube 36 is provided with an annular groove into which projects the end of a screw 40 extending through a nut 42 on the end of the pin 38. A compression spring 44 bears against the nut 42 at one end and the hub of the arm 32 at the other end, thus holding the end of the arm 32 in a socket formed in the end of its respective set plunger 24. When it is desired to remove one of the set plungers 24 from the machine to replace a set, the arm 32 may be moved toward the left against the action of the spring 44 thus disengaging the plunger and permitting its removal. When it is desired to remove one of the punch plungers 26 the nut 42 is turned and the threaded pin 38 is forced toward the right carrying the arm 34 with it which is thus disengaged from its respective plunger. Longitudinal movement of the nut 42 upon the tube 36 is prevented by the pin and slot connection above described.

A punching plate 50 is secured to the head 10 and extends forwardly between the branches thereof being provided adjacent to its outer end with a hardened punching block or anvil 52 which is thus held in alignment with and between the punches 27 on the inner ends of the punch plungers 26. The punch plate 50 is permanently secured to the head 10 and is movable with it and the punches forwardly into punching position, as shown in Fig. 4, and then rearwardly into an inoperative position as shown in Fig. 6 by the action of the cam 12 and the lever 8 as above outlined.

Each set plunger 24 carries at its inner end an upsetting die 25 which may be of suitable size and shape to accommodate the eyelets which it is desired to set. As herein shown, each upsetting die is provided with an outwardly extending upsetting shoulder adapting the set for invisible eyelet work. In the construction herein shown, the large diameter of the shoulder is small enough to be forced through the leather or outer part of the upper so that the shoulder will be positioned properly to clinch the eyelet barrel upon the lining and beneath the outer part of the upper. When the head 10 is moved rearwardly, as above explained in connection with the punches, the upsetting dies 25 are brought into alignment with the holes in the previously punched work as shown in Fig. 6.

The two sides of the upper are held in position during its progress through the machine by an intermediate guide plate 60 secured to a portion of the stationary frame 2 and extending adjacent to the die plate 50 when the latter occupies its initial position. Spring presser feet 62 held in place by leaf springs 64 are mounted upon opposite sides of the guide plate 60 and hold the work 10 yieldingly against the opposite surfaces of the plate.

A double raceway 70 having upper and lower eyelet tracks and an intermediate plate 72 is arranged to oscillate laterally in the 15 machine, first to position the endmost pair of eyelets in alignment with and beneath the holes in the work and the upsetting dies 25, then outwardly slightly and finally outwardly again to an inoperative position.

Eyelets are supplied to the raceway 70 from 20 a hopper 75 and approach the delivery end of the raceway with their flanges against the opposite faces of the intermediate plate 72 and their barrels pointing in opposite directions. The endmost eyelet in each side of the raceway is yieldingly held in place by a spring latch 74. The raceway and punching plate 50 are so shaped as to permit the end of the raceway to occupy the position 25 formerly occupied by the anvil 52 when the head 10 is moved rearwardly after the punching operation and the raceway is swung toward the right. The endmost eyelets are thus presented between the spaced 30 sides of the upper in alignment with the holes already formed therein. The intermediate plate 72 of the raceway projects outwardly beyond the ends of the eyelet track and is provided with a setting die 76 shaped to fit the flange of the eyelets being 35 used. In the case of the eyelets used in invisible work and having substantially flat flanges, the setting die 76 may be dispensed with and the eyelets supported directly by 40 the intermediate plate 72.

Having now described the construction of the machine its manner of operation will be set forth. The machine comes to rest with its parts in the positions shown in Figs. 1 and 4, the raceway 70 being swung outwardly to its inoperative position and the head 10 being held in its forward position. The operator presents a folded upper to 45 the machine with its lining portions extending upon opposite sides of the guide plate 60 and the punch plate 50 and the point at which the first eyelets are to be set in alignment with and between the anvil 52 and the punches 27. When the machine 50 is started the punches 27 are immediately advanced and coöperate with the anvil 52 to punch a hole in each side of the upper as indicated in Fig. 5 of the drawings. The punches are then retracted and the head 10 shifted toward the rear of the machine 55

whereupon the raceway 70 is swung toward the right carrying the endmost pair of eyelets into the position formerly occupied by the anvil and in alignment with the upsetting dies 25 which now occupy the positions 70 formerly held by the punches. Figs. 6 and 8 illustrate the parts of the machine in this condition. The upsetting dies 25 are then advanced into the holes in the work and into engagement with the barrels of the eyelets 75 in the raceway. The raceway is then moved toward the left while the eyelets are held stationary by the setting dies 25 until the set 76 is brought between the flanges of the eyelets. The upsetting dies are then further 80 advanced to clinch the ends of the eyelet barrels as shown in Fig. 7, the position of the raceway at this time being shown in Fig. 9. The setting dies are then retracted sufficiently to release their pressure on the plate 72, but not sufficiently to release the eyelets, and then the head 10 is swung toward the left feeding the work with it the distance required between successive eyelets. The raceway 70 swings toward the left at the 90 same time so as to allow free movement of the feeding tools. At the completion of the feeding movement the upsetting dies are retracted and the moving parts of the machine are returned to their initial position. During 95 the feeding movement and also after the punches have been withdrawn from the work, the work is held in place and guided in its movement by the guide plate 60 and the presser feet 62. In initial position the 100 end of the intermediate plate 72 of the raceway enters a recess 66 in the left hand wall of the guide plate 60 thus permitting a more compact arrangement of the parts than would otherwise be possible.

In using the machine to insert ordinary eyelets the upper is presented to the machine inside out and the upsetting dies 24 are shaped to clinch an eyelet barrel passing entirely through the work.

Having thus described my invention, I claim as new and desire to secure by Letters Patent of the United States:

1. A duplex fastener setting machine having, in combination, means for delivering 115 a pair of fasteners in setting position with their barrels facing away from each other, and means for upsetting said barrels.
2. A duplex fastener setting machine having, in combination, a double raceway comprising an intermediate plate upon the opposite sides of which eyelets are arranged to be fed with their barrels extending outwardly, and means for upsetting successive pairs of eyelets while they occupy such relation.
3. A duplex fastener setting machine having, in combination, an eyelet raceway having a plate extending from its end, and means for upsetting an eyelet supplied by 130

the raceway while the eyelet is supported by the plate.

4. A duplex fastener setting machine having, in combination, a double raceway for eyelets having a plate extending from its end, and means for upsetting simultaneously two eyelets delivered from the raceway and supported by the plate.

5. A duplex fastener setting machine having, in combination, means for supporting an upper with its sides in spaced relation, means for feeding successive pairs of eyelets in setting positions between the sides of the upper, and upsetting dies for clenching simultaneously each pair of eyelets.

6. A duplex fastener setting machine having, in combination, means for delivering a pair of eyelets in setting position with their barrels facing away from each other, setting dies for clenching the eyelets while they are maintained in such relation, and means for feeding the work intermittently after each setting operation.

7. A duplex fastener setting machine having, in combination, punches for punching holes in the two sides of a folded upper, means for inserting eyelets from inside the upper through said holes, and upsetting dies for clenching both eyelets and feeding the work.

8. A duplex fastener setting machine having, in combination, punch and anvil mechanism for perforating two sides of an upper, means for holding the upper in place after it has been so perforated, means for inserting a pair of eyelets from inside the upper in the perforations, and oppositely arranged upsetting dies.

9. A duplex fastener setting machine having, in combination, a raceway for eyelets, a punch for perforating the work, means for alining the perforation formed by the punch with an eyelet in the raceway, and a setting die movable through the perforation to engage the eyelet in the raceway.

10. A duplex fastener setting machine having, in combination, a raceway for eyelets, a punch for perforating the work, the work and raceway being then relatively moved to aline the perforation in the work with the endmost eyelet in the raceway, and a setting die movable through the perforation to engage the eyelet before it is removed from the raceway.

11. A duplex fastener setting machine having, in combination, a raceway for fasteners, means for perforating the work and positioning it with the hole in line with the endmost fastener in the raceway, and a feeding device arranged to enter said endmost fastener through the hole in the work.

12. A duplex fastener setting machine having, in combination, a movable anvil member, a punch coöoperating therewith to perforate the work, means for moving the anvil

member, and a raceway movable to locate its endmost eyelet in the position formerly occupied by the anvil member, said raceway being constructed and arranged to support the eyelet during the setting operation.

13. A duplex fastener setting machine having, in combination, a work support, a punching device, a coöperating anvil, a raceway, said anvil and raceway being movable alternately in a plane between the pieces of work and into a predetermined position with reference to the work, and an upsetting die arranged to operate subsequently at a point in alinement with said position.

14. A duplex fastener setting machine having, in combination, an anvil plate arranged to be shifted rearwardly after the punching operation, a punching anvil carried thereby, a raceway mounted to swing into the position previously occupied by the anvil, and means coöoperating with the raceway for clenching a fastener while it is supported by the raceway.

15. A duplex fastener setting machine having, in combination, a raceway having a support for a fastener during the setting operation, feeding means for setting a fastener on the support, and means for simultaneously moving the raceway and feeding means in the same direction.

16. A duplex fastener setting machine having, in combination, means for holding two eyelets with their barrels pointed outwardly, means for supporting a lined upper with its lining adjacent to the ends of the eyelet barrels, and upsetting dies for simultaneously clenching the eyelet barrels upon the lining and inside the outer portion of the upper.

17. A duplex fastener setting machine having, in combination, means for supporting a lined upper with its sides in spaced relation, and means for simultaneously inserting eyelets in the lining at each side of the upper and clenching them inside the outer portion of the upper.

18. A duplex fastener setting machine having, in combination, means for supporting a lined upper with its lined sides facing each other, and a pair of shouldered upsetting dies movable through the outer portion of the upper to clench the ends of the eyelet barrels upon the lining.

19. A duplex fastener setting machine having, in combination, means for supporting a lined upper with its lined sides facing each other, and means for alternately punching a pair of alined holes through both parts of each side of the upper and setting a pair of eyelets in the lining only.

20. A duplex fastener setting machine having, in combination, a head, a tubular journal member set therein, a lifting arm mounted on the journal member, a threaded pin passing through said member and carrying

a second lifting arm, and a threaded nut on said pin held against longitudinal movement but rotatable to shift the pin.

21. A duplex fastener setting machine having, in combination, a head carrying a plunger, a lifting arm for the plunger, a longitudinally movable pin carrying said arm, and means for positively moving the pin to disengage the arm and plunger.
- 10 22. A duplex fastener setting machine having, in combination, a raceway for eyelets, a punch for perforating the work, means for alining the perforation formed by the punch with an eyelet in the raceway, and a setting die movable from that side of the work which is opposite the eyelet through the perforation to engage the eyelet in the raceway.
- 15 23. A duplex fastener setting machine having, in combination, a raceway for eyelets, a punch for perforating the work, the work

and raceway being then relatively moved to aline the perforation in the work with the endmost eyelet in the raceway, and a setting die movable from that side of the work which is opposite the eyelet through the perforation to engage the eyelet before it is removed from the raceway.

24. A duplex fastener setting machine having, in combination, a raceway for fasteners, means for perforating the work and positioning it with the hole in line with the endmost fastener in the raceway, and a feeding device arranged to enter said endmost fastener through the hole in the work from that side of the work which is opposite the fastener.

In testimony whereof I have signed my name to this specification.

WALTER SHAW.
